UNITED STATES PATENT OFFICE.

CLINTON R. HANNA, OF WILKINSBURG, PENNSYLVANIA, ASSIGNOR TO WESTINGHOUSE ELECTRIC & MANUFACTURING COMPANY, A CORPORATION OF PENNSYLVANIA.

LOUD-SPEAKING TELEPHONE.

Application filed August 28, 1924. Serial No. 734,607.

This invention relates to sound-reproducing devices such as telephone receivers and loud speakers.

In the co-pending applications of Joseph Slepian, Serial No. 734,609, filed Aug. 28, 1924, for a microphone circuit, of Joseph Slepian and myself, Serial No. 734,608, filed Aug. 28, 1924, for a sound-translating device, and of myself, Serial No. 734,605, filed Aug. 28, 1924, for a microphone, all assigned to Westinghouse Electric and Manufacturing Company, various inventions are set forth which improve the faithfulness with which the current in the output of a microphone represents the sound impressed upon the instrument. One object of this invention is to provide for similar improvements in the faithfulness with which the sound from a sound-reproducing instrument represents the current impressed upon such instrument.

A further object of this invention is to provide a telephone receiver with a regenerative device.

A further object of this invention is to compensate for the inertia and stiffness of the diaphragm in a telephone receiver.

A further object of this invention is to provide means, whereby the magnet actuating a telephone receiver shall be subject, not only to control by the signalling current, but also to a supplemental control correlated to the movement of the receiver diaphragm.

A further object of this invention is to provide means whereby a regenerative action may be obtained in a telephone receiver and a supplemental means whereby this reaction will be prevented from rendering the receiver unstable.

Other objects and structural details of my invention will be apparent from the following description when read in connection with the accompanying drawing, wherein:

The single figure is a diagrammatic representation of the apparatus and circuits embodying the invention.

A loud speaker or other telephone receiving device, indicated in dotted lines, is provided with a diaphragm 1 actuated by an electromagnet 2. This electromagnet is in the output circuit of a tube 3 which is in the second stage of an amplifier. The first stage includes a tube 4.

The input of the tube 4 is supplied from the secondary of a transformer 5, the pri-

mary of which is connected to any source of signalling current. The source of signalling current is not illustrated since any source may be used. It is only necessary that the received current shall represent the sound to be reproduced.

A coil 6 is so associated with the diaphragm 1 that movement of the diaphragm causes a changing electromotive force in the coil 6. The coil 6 is connected to the input of the tube 4 through conductors 7 and 8. In the conductor 7, a condenser 9 and an inductor 11 are inserted, in parallel to each other. The conductors 7 and 8 are connected to the input circuit of the tube 4 on opposite sides of a resistor 12. A small inductor 13 is also included in series with the resistor 12 between said connections.

The conductor 8 includes a winding 14 which is inductively related to a winding 15 in the output circuit of the tube 3.

In the operation of the device, signalling current in the primary of the transformer 5 induces an electromotive force in the secondary which is impressed upon the grid of the tube 4. The output of this tube induces similar potential changes in the input of the tube 3 with the usual amplifying action. The energy for the amplification is supplied by the plate battery 16.

The output of the amplifier energizes the electromagnet 2 and causes the diaphragm 1 to vibrate. The diaphragm possesses a natural resonance frequency which is very largely determined by its stiffness and its mass. If, therefore, the action of the magnet 2 upon the diaphragm 1 is so modified as to produce changes in the forces exerted upon the diaphragm 1, and if the changes correspond to the reactions due respectively to the inertia and the stiffness of the diaphragm, resonance will either be greatly reduced or eliminated altogether.

The movement of a diaphragm, being a harmonic motion, may be represented by a rotating vector. If the rotating vector is a representation of the displacement, a vector 90° in advance of it will represent the velocity. The acceleration will be represented by a vector 90° in advance of the velocity, that is, opposed to the displacement.

The inertia reaction is a reaction opposed to the acceleration. It is, therefore, represented by a vector in phase with the displacement. The stiffness reaction is a reaction

opposed to the displacement. It is, therefore, a vector in phase with the acceleration. Damping is a force opposed to the velocity and is properly represented by a vector 180° different in phase from the velocity vector.

All of these vector relations are familiar to those skilled in the art and all, except the last, are readily recognized as a necessary consequence of the fact that the motion of a 10 diaphragm is harmonic.

Damping is a force brought into existence by the velocity. For example, if the damping be friction, it is readily recognized that when the diaphragm is still, there is no force 15 exerted by friction; that when the diaphragm moves slowly, only slight friction is present; and that when the diaphragm moves rapidly, the force exerted by friction will be great. The propriety of describing damping as a 20 force of the same phase as the velocity, but opposed in direction to it, will, therefore, be evident. The general, as opposed to technical use of the term "damping," makes it apply to any force which, in any way, tends 25 to bring the diaphragm to rest. In this specification and in the claims "damping" is used, not in its general sense, but in its technical sense.

At low frequencies, the predominating reaction is that due to stiffness. Also, at low 30 frequencies, the reactance of the condenser 9 is the predominating factor in the circuit 7-8. At high frequencies the mass has a greater effect than the stiffness. Also, at 35 high frequencies, the reactance of the inductor 11 is the predominating element in the circuit 7-8. At the resonance frequency the reactions due to stiffness and inertia very 40 largely compensate each other. At this frequency, therefore, it is undesirable that energy from the coil 6 be delivered to the grid circuit of the tube 4.

The delivery of energy from the diaphragm back to the control circuit may 45 properly be called regeneration. At the resonance frequency, regeneration is prevented because, for this frequency, the parallel connection, including the condenser 9 and the inductor 11, is resonant. Regeneration is, 50 therefore, prevented at the very frequency where it is undesired.

At other frequencies, an electromotive 55 force is introduced across the resistor 12 and the inductor 13. The phase of this electromotive force must be such that, at all times, it so corrects the electromotive force from the secondary of the transformer 5 that the potential impressed upon the grid of the tube 4 is modified to compensate for the 60 reactions in the diaphragm.

The impedance of the inductor 13 is very small as compared with that of the resistor

12. It does, however, produce a slight effect upon the phase of the correction just mentioned. This effect is needed because the 65 acceleration of the diaphragm is not strictly in phase with the current in the coil 2, and the electromotive force generated in the coil 6 is not strictly in phase with the velocity of the diaphragm. The lead of the electromotive force across the impedance 12-13, secured by making this impedance slightly inductive, is sufficient to ensure that the instrument will not set itself into oscillation.

A more detailed discussion of the effect of 70 the reactances of condenser 9, inductor 11 and inductor 13 upon the phase of the force exerted by coil 2 is given in the above identified co-pending joint application.

Although the coil 2 and the coil 6 are illustrated as upon opposite sides of the diaphragm 1, they are in ordinary constructions incompletely shielded from each other. There is some slight coupling between them. To compensate for the effect of such coupling upon the phase of the above-mentioned 85 correction, the transformer 14-15 is introduced.

While I have shown only one embodiment 90 of my invention in the accompanying drawings, it is capable of various changes and modifications without departing from the spirit thereof, and it is desired, therefore, that only such limitations shall be imposed 95 thereon as are required by the prior art or indicated in the appended claims.

I claim as my invention:

1. In a sound-producing device, a diaphragm, magnetic driving means for said diaphragm, and means controlled by the 100 movement of said diaphragm for impressing on said magnetic driving means a supplemental current of a phase in quadrature with the velocity of said diaphragm.

2. In a sound-reproducing device, a diaphragm, a signal circuit, an amplifier having an input circuit, a driving means for 105 said diaphragm, said amplifier having an output circuit solely energizing said driving means, means for impressing on the input 110 circuit of said amplifier an electromotive force corresponding to the movement of said diaphragm, and means for so determining the phase of said electromotive force that the reactions due to stiffness and inertia of the 115 diaphragm are counteracted, the phase of said electromotive force being such that the component thereof tending to produce damping is small relative to either of said reactions.

In testimony whereof, I have hereunto 120 subscribed my name this 22nd day of August 1924.

CLINTON R. HANNA.
